WITNESS *P. B. Hickey.*

ATTORNEY

UNITED STATES PATENT OFFICE

2,142,479

GARMENT

Herbert Rosenfelder, Columbus, Ohio

Application November 29, 1935, Serial No. 52,245

1 Claim. (Cl. 2—70)

This invention relates to garments for either adults or children, and has for the primary object the provision of a two piece garment equipped with quick detachable fasteners in the form of 5 slidable fasteners wherein the pieces of the garment may be either partly or wholly separated from each other and readily joined and when only partly separated, the seat of the trousers portion may be allowed to lower to a full buttock 10 uncovering position.

With these and other objects in view, this invention consists in certain novel features of construction, combination and arrangement of parts to be hereinafter more fully described and 15 claimed.

For a complete understanding of my invention, reference is to be had to the following description and accompanying drawing, in which—

Figure 1 is a perspective view showing the 20 garment worn by a child and constructed in accordance with my invention.

Figure 2 is a rear elevation illustrating the trousers portion partially detached from the waist or shirt portion to permit lowering of the 25 seat of the trousers portion.

Figure 3 is a view showing the two piece garment connectible by a quick detachable fastener.

Figure 4 is a fragmentary plan view illustrating a fastener for detachably connecting the portions 30 of the garment.

Figure 5 is a perspective view showing a slight modification of garment adapting the same for adult use.

Referring in detail to the drawing, the numeral 35 1 indicates a waist portion and 2 a trousers portion. The adjacent edges of these portions are detachably connected by a separable fastener 3, one portion of which is fixed to the lower edge of the waist portion, as shown at 4, while the 40 other portion is fixed to the upper edge of the trousers portion and releasable from the waist portion by means of a slide 5, thereby bringing about a complete separation of said portions.

The trousers portion at one side is provided 45 with a slit 6 closed by a separable fastener 7

which permits the trousers portion to be opened at one side and thereby facilitate the putting on and taking off of the trousers portion and permits said trousers portion to be of a form-fitting design.

During wearing of the garment and it is desired to lower the seat portion, the slide 5 of the fastener is moved to the opposite side of the garment and the slide 7 is pulled downwardly, allowing the seat to lower, as shown in Figure 2, 10 providing a comparatively large opening in the trousers portion to expose the buttock.

The garment shown in Figure 5 is of the form-fitting type designed for adults and includes a waist portion 8 and trousers portion 9, the portions 8 and 9 being detachably connected by a 15 slidable fastener 10. The waist and trousers portions at one side are slit or slotted, as shown at 11. The slotted portions of the waist and trousers portions are normally closed by fasteners 12. The fasteners 10 and 12 permit the form-fitting garment to be readily opened or the waist 20 and trousers portions thereof to be completely separated.

While I have described the garment being slit at the side, it is to be understood the slit may be omitted, as shown in Figure 3.

The fastener at one end has a stud 13 to extend in the slot 14 of the finger piece or movable end 30 of the fastener to act as a catch, as shown in Figure 4.

Having described the invention, I claim:

A garment including nether and waist portions, said nether portion having a vertically disposed slot at an axilar side of the garment, separable fastener means for said vertical slot, a slide member for said separable fastener means, separable fastener elements carried by the horizontal confronting edges of said nether and waist portions completely encircling the waist portion, and a slide member for said latter separable fastener elements starting at the said axilar side of the garment.

HERBERT ROSENFELDER.
